UNITED STATES PATENT OFFICE.

WALTER H. COTTON, OF CHICAGO, ILLINOIS.

SPARK-PLUG.

1,340,526.

Specification of Letters Patent. Patented May 18, 1920.

Application filed March 4, 1919. Serial No. 280,633.

To all whom it may concern:

Be it known that I, WALTER H. COTTON, a citizen of the United States of America, and resident of Chicago, county of Cook, and State of Illinois, have invented certain new and useful Improvements in Spark-Plugs, of which the following is a specification, and which are illustrated in the accompanying drawings, forming a part thereof.

10 The invention relates to spark plugs and especially to those which are known as self-cleaning spark plugs and which are constructed to secure, when used with internal combustion engines, a vigorous sweep of the 15 gases over the surface upon which accumulations of carbon or the like might serve to short circuit the electrodes. The invention contemplates an improved spark plug of the type indicated, and among the objects of the 20 invention is a construction wherein the self-cleaning feature is developed in a form which may be easily and cheaply manufactured and which is effective and durable in use. Other objects of the invention will appear from the following description.

25 In the accompanying drawings;—

Figure 1 is a side elevation showing one form of the improved spark plug,

Fig. 2 is a central longitudinal sectional 30 view of the same,

Figs. 3 and 4 are bottom and top plan views of the same respectively, and

Fig. 5 is a plan sectional view taken on the line 5—5 of Fig. 2.

35 In carrying out the invention a metal holder, generally designated 10, is preferably provided. As shown, this holder comprises a socketed body 11 and a tubular threaded stem 12, the bore 13 of the stem 40 being of relatively small diameter. The stem 12 may thus be exteriorly formed in different sizes without varying the dimensions of the device in other respects. The grounded electrode, as 14, is mounted upon 45 the outer end of the stem 12 in the usual manner.

The insulated electrode 15 is mounted in the insulating block 16 to extend centrally through the bore of the stem 12 as usual except that owing to the small size of the bore 13 the annular gap between the electrode 15 and the walls of the stem 12 is relatively short and preferably contains no solid insulating shield. The lower end of

the insulating block 16 fits within the socketed body 11 of the holder 10 and is firmly secured therein, as by a clamping nut 17.

In this spark plug, the construction affords a chamber, as 18, of substantial size into which a part of the explosive charge of an internal combustion engine (not shown) is compressed. The present invention contemplates the formation of the chamber 18 within the insulating block 16 without requiring the use of a core in the production of the block. For this purpose the insulating block 16 is preferably made of relatively long and narrow cylindrical form and is hollow throughout a substantial part of its length extending from the lower end of the same, the chamber 18 thus produced being, however, as large in diameter at its lower end as in any other portion. At its upper end the block 16 is closely fitted about the electrode 15 which is firmly held thereby in any convenient manner, as by the use of a clamping nut 19.

A restricted outlet for the chamber 18 is provided by forming the electrode 15 with an enlarged portion 20 which is located 80 within the chamber 18 but adjacent the open end of the same. A narrow annular outlet passage 21 for the chamber 18 is thus provided between the near wall of the block 16 and the exterior of the surface of the enlarged portion 20 of the electrode 15 adjacent the open end or mouth of the said chamber. Both in entering and leaving the chamber 18 the gases which are compressed 85 therein will sweep rapidly over the surface of the enlarged portion 20 of the electrode 15 and the adjacent surface of the block 16 for keeping these surfaces free from accumulations of any kind. There will also be a rapid movement of the gases through the bore 13 of the stem 12 about the corresponding part of the electrode 15 and the compression of a considerable volume of gas within the chamber 18 tends to insure that a part 90 of the fresh charge of gas will be brought 100 into the immediate proximity of the spark gap between the electrodes 14—15.

While the part 20 has been referred to as an enlarged portion of the electrode 15 this part need not be formed integral with the electrode and may take the form of a bushing of insulating material mounted upon the electrode. The use of the enlargement 20

upon the electrode 15 serves to provide a restricted outlet for the chamber 18 without requiring the walls of this chamber to be formed with any under cutting portions which would necessitate the use of cores or the like in the production of the block 16. Furthermore, as the walls of the chamber 18 are straight throughout the length of the chamber the block 16 is of increased strength and is not likely to become broken in use.

10 I claim as my invention—

15 1. In a spark plug, in combination, a cylindrical electrode-carrying member of insulating material having a chamber extending longitudinally within the same throughout a substantial part of its length and opening at one end of the said member, the other end of the member being closed and the chamber being as large in diameter at its 20 mouth as in any part of the same, and an electrode fixed in the said carrying member and extending through its chamber to and outwardly beyond the mouth of same, a part of the electrode within the chamber but adjacent its mouth bearing an enlargement to provide a restricted annular passage of substantially less cross-sectional area than that of the chamber inwardly beyond such enlargement, said passage adapted to allow 25 gases to surge into and out of said chamber.

30 2. In a spark plug, in combination, a cylindrical electrode-carrying member of insulating material having a chamber extending longitudinally within the same throughout a substantial part of its length and opening at one end of the said member, the other end of the member being closed, and an electrode fixed in the said carrying member and extending through its chamber to and outwardly beyond the mouth of the same, a 35 part of the electrode within the chamber but adjacent its mouth bearing an enlargement to provide a restricted annular passage of substantially less cross-sectional area than that of the chamber inwardly beyond such enlargement, said passage adapted to allow 40 gases to surge into and out of said chamber.

45 3. In a spark plug, in combination, a cylindrical electrode-carrying member of insulating material having a chamber extending longitudinally within the same throughout a substantial part of its length and opening at one end of the said member, the other end of the member being closed and the chamber being as large in diameter at its 50 mouth as in any part of the same, an electrode fixed in the said carrying member and extending through its chamber to and outwardly beyond the mouth of the same, and a bushing of insulating material mounted 55 upon the electrode within the chamber of the carrying member but adjacent its mouth to provide a restricted annular passage of substantially less cross-sectional area than 60 that of the chamber inwardly beyond the 65

said bushing, said passage adapted to allow gases to surge into and out of said chamber.

4. In a spark plug, in combination, a metallic socketed holder, an electrode carrying member of insulating material seated in said holder, said member having a chamber with a mouth equal to its greatest diameter, an electrode fixed in said member bearing an enlargement in the mouth of said chamber providing a restricted annular passage of 75 greater width than the spark gap for surge of gases, and a spark gap between said electrode and holder exterior of said passage.

5. In a spark plug, in combination, a metallic holder having a socketed body and a 80 tubular stem, a cylindrical electrode-carrying member of insulating material fixed at one end in the socket of the holder and having a chamber extending longitudinally within the same throughout a substantial 85 part of the length of the member and opening at the said end of the member in line with the bore of the stem of the holder, the other end of the said insulating member being closed and its said chamber being as 90 large in diameter at its mouth as in any part of the same, an electrode fixed in the closed end of the insulating member and extending through its chamber and through the bore of the stem of the holder, a part of 95 the electrode within the chamber of the insulating member but adjacent the mouth of said chamber bearing an enlargement to provide a restricted annular passage of substantially less cross-sectional area than that of 100 the said chamber inwardly beyond such enlargement, and a second electrode mounted on the stem of the holder.

6. In a spark plug, in combination, a metallic holder having a socketed body and a 105 tubular stem, a cylindrical electrode-carrying member of insulating material fixed at one end in the socket of the holder and having a chamber extending longitudinally within the same throughout a substantial 110 part of the length of the member and opening at the said end of the member substantially in line with the bore of the stem of the holder, the other end of the said insulating member being closed and its said chamber 115 being as large in diameter at its mouth as in any part of the same, an electrode fixed in the closed end of the insulating member and extending through its chamber and through the bore of the stem of the holder, a bushing 120 of insulating material mounted upon the said electrode within the chamber of the insulating member but adjacent the mouth of the chamber to provide a restricted annular passage of substantially less cross-sectional 12 area than that of the said chamber inwardly beyond the said bushing, and a second electrode mounted on the stem of the holder.

WALTER H. COTTON,
